EGG TRAY

Clifford H. Bessett, South Holland, Ill., assignor to
Packaging Corporation of America, Evanston, Ill.

Filed Jan. 17, 1969, Ser. No. 15,391

Term of patent 14 years

Int. Cl. D9—04

U.S. Cl. D9—190

FIG. 1.

FIG. 2.

FIG. 3.

FIG. 4.

FIG. 5.

FIG. 6.

FIG. 1 is a bottom perspective view of an egg tray showing my new design;

FIG. 2 is a top plan view thereof;

FIG. 3 is a front elevation thereof;

FIG. 4 is a fragmentary bottom plan view thereof;

FIG. 5 is an end elevation thereof; and

FIG. 6 is a top perspective view thereof.

The design is characterized by a blending of small, substantially triangular indentations into the sides of the pockets or cells of the egg tray, all as shown.

I claim:

The ornamental design for an egg tray, substantially as shown and described.
